Primary Examiner — Wendy L Arminio*Assistant Examiner* — Tracey J Bell(74) Attorney, Agent, or Firm — Koffsky Schwalb LLC; Mark I. Koffsky(57) CLAIM

I claim the ornamental design for a zipper, as shown and described.

DESCRIPTION

FIG. 1 is an upper perspective view of a zipper in accordance with the present invention;

FIG. 2 is a lower perspective view of a zipper in accordance with the present invention;

FIG. 3 is a top view thereof;

FIG. 4 is a bottom view thereof;

FIG. 5 is a left view thereof;

FIG. 6 is a right view thereof;

FIG. 7 is a front view thereof; and,

FIG. 8 is a rear view thereof.
